UNITED STATES PATENT OFFICE.

EUGEN BARON RITTER AND CARL KELLNER, OF PODGORA, NEAR GOERZ,
AUSTRIA-HUNGARY, ASSIGNORS TO WILLIAM A. RUSSELL, TRUSTEE, OF
LAWRENCE, MASSACHUSETTS.

PROCESS OF MAKING SOLUTIONS OF BISULPHITES.

SPECIFICATION forming part of Letters Patent No. 329,216, dated October 27, 1885.

Application filed February 4, 1885. Serial No. 154,861. (No specimens.) Patented in Austria-Hungary August 2, 1883, No. 20,024 and No. 31,730; in France September 27, 1883, No. 157,754; in Belgium September 29, 1883, No. 62,746, and in Italy January 22, 1884, No. 16,316.

To all whom it may concern:

Be it known that we, EUGEN BARON RITTER and CARL KELLNER, subjects of the Emperor of Austria-Hungary, residing at Podgora, near 5 Goerz, Austria-Hungary, have invented a certain new and useful Process of Producing Double-Salt Bisulphite Solutions for the Manufacture of Cellulose or Paper-Pulp, (the said invention having been patented to us in Italy o January 22, 1884, No. 16,316; in France September 27, 1883, No. 157,754; in Belgium September 29, 1883, No. 62,746, and in Austria-Hungary August 2, 1883, No. 20,024 and No. 31,730;) and we do hereby declare the following to be a full, clear, and exact description of the invention, reference being had to the accompanying drawings, which form part of this specification, in which—

Figure 1 is a vertical transverse section of the apparatus employed for carrying our invention into effect. Fig. 2 is a horizontal section of the same. Fig. 3 is a vertical longitudinal section, and Fig. 4 a sectional view of a detail.

5 In an application of even date herewith we have described and shown the apparatus constituting the plant for the production of bisulphites by the combination of sulphurous acid with a suitable base or bases, and this 30 application is intended to embody the process which said apparatus is best adapted to carry into effect.

As a process, our present invention consists in first subjecting the carbonate of a base to 35 the action of sulphurous acid, whereby the carbonic acid is expelled and the sulphite so formed dissolved in the weakened acid solution, and then reimpregnating the sulphite solution with sulphurous acid, and again effecting a combination with the second base and the formation of a double salts, in which more than two molecules of the acid are combined with one molecule of each base.

40 The apparatus for carrying out the process which forms the subject-matter of the present application having been made the subject-matter of another application, as aforesaid, we

will herein describe the same, but briefly, so as to facilitate the understanding of the various steps of the process, and without describing 50 in detail the minor parts.

This apparatus may be stated to consist of the following elements, namely: an absorption-chamber, A, subdivided into communicating compartments B C D E F, provided with 55 gratings to receive coke or limestone, and connected through suitable pipes and sluice-valves with a gas-supply; a series of liquid reservoirs, G H I J K, on top of and communicating respectively with said compartments; a series of 60 basins, L M N O P, with pipes leading to said reservoirs by way of intermediate pumps or delivery devices, and with said compartments by means of discharge pipes or conduits, whereby the gases and liquids are caused to 65 circulate through said compartments in opposite directions; boxes Q R, adapted to contain carbonates of the bases; meters S T, arranged at the entrance and discharge ends of 70 said boxes and communicating therewith, and pipes leading in series from one compartment of the absorption-chamber to the box Q, thence to the reservoir-basin P, next to the compartment F, thence to the box R, and finally to the reserve basin P'.

75 The successive steps of our process are as follows: The compartments B C D E F are first charged with coke or limestone and the boxes Q R with layers of carbonate deposited in a methodical manner. Now sulphurous acid is 80 admitted from the supply through one or the other of the sluice-boxes to the compartments, through which it circulates *seriatim*, while at the same time water is led from the basin L, by way of the reservoir K, to the compartment 85 F, whence it circulates in opposition to the gases through the basins and the compartments and reservoirs in their order until the compartment C is reached, after which it passes into the box Q and over the layers of 90 carbonate contained therein. At this stage the sulphurous-acid solution chemically combines with the base contained in the box Q, producing a sulphite solution. Leaving the box Q,

the sulphite solution passes into the basin P, and is from this basin conveyed into the compartment B, where it again meets the sulphurous acid and is again impregnated. Leaving compartment B, the sulphite solution is conveyed to the box R, wherein it meets the carbonates of the second base, combines therewith, and is converted into a double salt having more than two atoms of sulphurous acid to one atom of the base.

Instead of carbonates, hydrates may be employed in the boxes Q R.

This process is materially assisted and accelerated by the momentary formation of bicarbonate, which is produced by the dissolving action of the liberated carbonic acid upon the adjacent portions of the carbonate, but is immediately converted by the stronger sulphurous acid into bisulphite. In practice we have found, however, that if the carbonates are employed in pieces they are coated with a covering of sulphite, which covering offers an obstacle in the way of further decomposition.

Having described our invention, we claim—

1. The process or method of producing a 25 solution of bisulphites, which consists in combining sulphurous acid with bases, in the proportion of more than two molecules of the acid with one molecule of each base, substantially as described.

2. The process of producing a solution of bisulphites, wherein sulphurous acid is combined with bases, in or about the proportions stated, said process being carried into effect by first bringing a solution of sulphurous acid 35 and water in contact with one of the bases, and thereby forming a sulphite solution, then re-impregnating the sulphite solution with sulphurous acid and bringing the same in contact with a second base, substantially as described. 40

In testimony that we claim the foregoing we have hereunto set our hands.

EUGEN BARON RITTER.
CARL KELLNER.
